UNITED STATES PATENT OFFICE.

JOHN J. BURKE, OF CINCINNATI, OHIO.

RACK FOR INDEXING-MACHINES.

SPECIFICATION forming part of Letters Patent No. 784,658, dated March 14, 1905.

Application filed July 1, 1904. Serial No. 214,856.

To all whom it may concern:

Be it known that I, JOHN J. BURKE, a citizen of the United States of America, and a resident of Cincinnati, county of Hamilton, State 5 of Ohio, have invented certain new and useful Improvements in Racks for Indexing-Machines, of which the following is a specification.

My invention relates to a rack for regulating the step-by-step feed of the table which 10 carries the books to be cut for the indices.

The object of my invention is a rack of this character which may be changed readily to adapt it for use in cutting varying-sized indices. This object is attained by the means de- 15 scribed in the specification and illustrated in the drawings, in which—

Figure 1 is a perspective view of a rack embodying my invention with only so much of the index-machine shown as is necessary to 20 understand my invention. Fig. 2 is a perspective view of the rack embodying my invention. Fig. 3 is a detail view of the key for clamping the teeth in the rack. Fig. 4 is a transverse sectional view of the rack upon 25 an enlarged scale. Fig. 5 is a detail perspective view of one of the end blocks of my rack. Fig. 6 is a similar view of one of the teeth. Fig. 7 is a similar view of one of the spacing-blocks. Fig. 8 is a detail perspective view of 30 the stop-block for checking the forward movement of the table at any predetermined point.

Referring to the parts, the rack A is to be secured firmly to the table, which carries the book to be indexed in a step-by-step movement beneath the cutting-knife to cut the index edge of the book in a well-known manner, such as shown in United States Letters Patent No. 360,330 to Charles Seybold. Upon the table a constant pressure is exerted either 35 by weight or by spring, tending to feed it forward. This forward motion is checked by means of a pawl or dog b, carried by a bell-crank lever B, which is pivoted at b' and has its arm b² coupled to a rod b³, whose upper 40 end passes through a bracket b⁴ and is pressed outward normally by a spring b⁵ in the path of a cam b⁶, mounted upon a constantly-rotating shaft b⁷, so that the upper end of the rod b³ is intermittently contacted by the cam to 45 allow the arm b² to raise the dog b and to al-

low the table to be carried forward one step. The parts thus far described are of ordinary construction and need not be more specifically described.

The rack embodying my invention consists 55 of a bar a, having cut in it a longitudinal tapered way a', the taper flaring outward in the bottom of the way. Upon one side of the way is placed a key C, which has dowel-pins c c', which pass through perforations a² upon 60 the side of the way a', so that the key C may be moved to be more or less closely in contact with the side of the way, so as to limit its size. The movement of the key C is regulated by means of set-screws c². 65

Adapted to fit the way a' are a series of teeth D, having tapered bases d to engage the way. The teeth are made, preferably, uniform in size. In conjunction with the teeth I use a series of spacing-blocks E, which are 70 formed in a shape similar to the base d of the teeth, but have no part which projects up above the upper surface of the bar a like the parts d' of the teeth D. At the ends of the racks I have placed end blocks F F', which 75 are perforated to receive thumb-screws f f'. I make use likewise of an enlarged spacing-block G, which I place in the rack adjacent to the end block F.

It is seen that with my construction a rack 80 may be formed in which the space between the teeth may be made of any size desired, so that irregular indexing may be carried on with an easy change upon the same rack. If an unusually large space is desired, all that is 85 necessary is to place several of the spacing-blocks E between one tooth and the next adjacent tooth. After the teeth and the intervening blocks have been placed in the way a' by removing one of the end blocks F or F' 90 and have been adjusted to the points desired they are clamped in position by means of the key C and the set-screws c². It is therefore necessary to have only one rack for each machine with the desired set of teeth and spacing-blocks, and when a book of a different index from the one previously cut is to be 95 made the rack may be changed easily for this work.

In Fig. 8 I have illustrated a stop-block for 100

checking the forward movement of the table at any predetermined point. Upon the inner side of the rack adjacent to the bell-crank lever B, I have made a series of screw-holes 5 α^2 , which are to be engaged by thumb-screws $h\ h'$, and have provided a block H, which has a longitudinal slot h^3 upon one end to be slipped over the thumb-screws $h\ h'$. Block H carries a stud h^4 , which projects outward 10 so as to contact the bell-crank lever B in the travel of the carriage. The thumb-screws $h\ h'$ may be placed in any two adjacent holes of the series α^2 , and then by regulating the position of the block upon the set-screws the 15 point at which the feed of the table will be stopped can be regulated to a nicety, so as to set the machine for cutting various-sized books, since when the stud h^4 contacts the bell-crank lever B while the cam may continue to allow the arm b^3 to be carried inward the stud h^4 prevents the carriage from moving forward.

What I claim is—

1. A rack for index-cutting machines consisting of a bar having a longitudinal groove therein, a series of independent teeth having bases to seat in the groove and a series of independent spacing-blocks having bases to seat 25

in the groove and means for clamping the bases of the teeth and of the blocks in the 30 groove.

2. A rack for index-cutting machines consisting of a bar having a longitudinal way cut therein, a longitudinal key seated in the way, independent teeth in the way and set-screws 35 for engaging the key and clamping the teeth in the way.

3. A rack for index-cutting machines consisting of a bar having a longitudinal inwardly-flaring groove, independent teeth having similarly-flared bases for engaging the groove, spacing-blocks having similar bases for engaging the groove and means for clamping the teeth and the blocks in the groove. 40

4. A rack for index-cutting machines having a series of perforations upon its side, a bell-crank lever carrying a pawl for engaging the rack, thumb-screws for engaging the perforations, and a block slotted for adjustment upon the screws and carrying a stud to engage 45 said lever to limit the travel of the rack.

JOHN J. BURKE.
